UNITED STATES PATENT OFFICE.

PHILLIP HIEN, OF CHICAGO, ILLINOIS.

FRICTION-SPRING.

SPECIFICATION forming part of Letters Patent No. 767,479, dated August 16, 1904.

Application filed December 17, 1902. Serial No. 135,572. (No model.)

To all whom it may concern:

Be it known that I, PHILLIP HIEN, a citizen of the United States, residing at Chicago, county of Cook, State of Illinois, have invented 5 a certain new and useful Improvement in Friction-Springs; and I declare the following to be a full, clear, and exact description of the same, such as will enable others skilled in the art to which it pertains to make and use the 10 same, reference being had to the accompanying drawings, which form a part of this specification.

My invention relates in general to apparatus for yieldingly resisting a strain or gradually absorbing a shock or sustaining a load, and more particularly to the type of such apparatus forming the subject-matter of pending application, Serial No. 116,187, filed by me on July 19, 1902, and of Patents Nos. 20 715,068 and 715,069, granted to me on December 2, 1902.

The expansion and compression of the open spring-rings incident to the operation of the character of apparatus covered by the pending application and patents referred to produce the greatest strain upon the portions of the rings opposite to the openings between the ends. In order that the strain may be effectively sustained, I provide in my present 25 invention rings of a graduated, radial, or transverse width, each ring where the greatest strain occurs being made of greater radial width than the rest of the ring, the width gradually diminishing in opposite directions toward 30 the ends of the ring.

By reference to Patent No. 715,069 it will be observed that the expansion and compression of the series of rings produce relative movements between the radial surfaces of the 40 rings and the adjacent radial surfaces of the flanges or plates interposed between the pairs of rings, as well as between the surface of each end expansible ring and the engaged surface of the adjacent follower. It is conse- 45 quently desirable that provision should be made for preventing the wear to which the plates and followers are subjected through the frictional contact of the rings therewith

forming grooves in the surfaces of the plates and followers, which would produce uneven 50 frictional contact.

The primary object of my present invention is to provide in an apparatus of the type referred to expandable and compressible resilient elements which will possess a maximum 55 tensile strength with a minimum amount of metal and to provide radial frictional surfaces to be engaged by the resilient elements which will withstand the wear incident to the operation of the apparatus without the formation 60 therein of grooves, and thereby insure permanent uniform frictional contact.

A further object of my invention is to provide an apparatus of the character referred to which will be simple in construction and effi- 65 cient and durable in use.

My invention will be more fully described hereinafter, with reference to the accompanying drawings, in which the same is illustrated as embodied in several convenient and practical forms, in which—

Figure 1 is a longitudinal sectional view showing the apparatus subjected to sufficient compression to remove the normal camber of the rings; Fig. 2, a view similar to Fig. 1, 75 showing the position of the parts when subjected to sufficient compression to expand and compress the rings; Fig. 3, a transverse view on line 3 3, Fig. 2; Fig. 4, an elevational view of one of the compressible rings; Fig. 5, an elevational view of one of the expansible rings; Figs. 6 and 7, plan views of the compressible and expansible rings, respectively; Fig. 8, a sectional view of one of the followers; Fig. 9, a view similar to Fig. 8, 85 showing a modification; Fig. 10, an elevational view looking from the right in Fig. 11; Fig. 11, a central sectional view through one of the end sections of the telescopic core; Fig. 12, a view similar to Fig. 11, illustrating 90 a modification; and Fig. 13, a longitudinal vertical section through the central section of the core.

Similar reference characters are used in the several figures of the drawings to indicate 95 similar parts.

The general construction and operation of the apparatus herein disclosed are fully described in my prior patent, No. 715,069. It will be only necessary in the present case to 5 describe the features of construction possessed by the invention herein disclosed over the apparatus illustrated and described in the patent referred to.

Referring particularly to Figs. 1 and 2, the 10 radial flange or plate E' is provided with a groove f' on the surface thereof, which is engaged by the radial surface of the adjacent compressible ring C'. The plate E' is also provided with an annular shoulder F', which 15 serves to retain the ring C' concentrically with respect to the end section D' of the core. A groove f'', similar to the groove f', is provided in the plate E' at a point adjacent to a circular flange e', which projects laterally 20 from the end section D' of the core. A shoulder F'' is also provided upon the surface of the plate E' to center the ring C' with respect to the end section D' of the core. The opposite surfaces of the radial flange or plate E 25 are provided with grooves f, located adjacent to the tubular flanges e' and e'', respectively, which project in opposite directions and constitute the central section D of the core. The opposite surfaces of the plate E are also provided with shoulders F, which are engaged by the compressible rings C' and C'' when the latter are in their expanded condition and serve to retain the rings concentrically with 30 respect to the section of the core which they surround.

In order that the expandable rings B' and B'' may not wear grooves in the surfaces of the followers A' and A'', which they engage, the surfaces of the followers are cut away, as 40 shown at a' and a'', respectively. The radial plates E and E' project only to the exterior of the expandable rings B' and B'' when they are in their expanded condition, as shown in Fig. 1.

When the apparatus is subjected to sufficient compression to effect an expansion and contraction of the several rings from the position shown in Fig. 1 to that shown in Fig. 2, the movement of the compressible rings 45 with respect to the surfaces which they engage on the plates or flanges merely wears away the material between the shoulders F, F', and F'' and the grooves f, f', and f'', respectively, and does not form an uneven surface 50 between the respective sections of the core and the shoulders F, F', and F'', as might otherwise occur if the grooves f, f', and f'' were not provided. In other words, if it were not for the grooves f, f', and f'' the surfaces on 55 the plates which are engaged by the rings might be worn more throughout the portion in constant engagement with the rings during their compression than would the portion between the rings in their expanded condi-

tion shown in Fig. 1 and the corresponding 65 section of the core.

In order to avoid the surfaces on the plates which are engaged by the expandable rings becoming uneven through the constant wear upon the portions thereof engaged by the 70 rings shown in Fig. 1 and the portions which are only engaged when the rings are expanded from the position shown in Fig. 1 to that shown in Fig. 2, the plates on the sections of the core do not extend beyond the 75 expandable rings when the latter are in their contracted position, (shown in Fig. 1;) while the surfaces on the followers are cut away throughout the portion thereof outside of the end expandable rings when the latter are in 80 their contracted position. Consequently the movement of the expandable rings relatively to the engaged surfaces merely tends to wear away the engaged surfaces evenly, as is evident from an inspection of Figs. 1 and 2. 85

In Fig. 8 I have illustrated a modified means of preventing the surface of the followers from being unevenly worn away by the end expandable rings, consisting in a ring G', of a metal capable of withstanding greater 90 frictional wear than is the material of which the followers are made. These rings may be loosely engaged with the followers by their surrounding the annular flange a', or the reinforcing-ring may be partially inserted within a groove formed in the follower, as shown in Fig. 9, in which figure H' indicates the reinforcing-ring of hard metal, which is partially embedded in the surface of the follower A' and surrounds the flange a' thereon. The 100 surfaces of the plates or flanges which extend radially from the several sections of the core are likewise reinforced by similar rings either surrounding the cylindrical portions of the core, as shown in Fig. 11, or partially embedded in the plates or flanges, as shown in 105 Figs. 12 and 13.

Referring more in detail to Figs. 10 and 11, G⁵ indicates a ring of hard metal which 110 loosely surrounds the cylindrical flange d' on the section D' of the core and is supported thereby. g³ indicates a ring of hard metal, which surrounds the tubular flange e' on the section D' of the core and is preferably provided with a shoulder G³ for centering the 115 compressible ring with respect to the core. The reinforcing-rings which are engaged by the compressible rings preferably terminate a sufficient distance from the exterior of the tubular projections on the sections of the core to leave a groove corresponding, in effect, to the grooves f, f', and f'', formed directly in the metal of which the sections of the core are formed in the construction illustrated in 120 Figs. 1 and 2. The rings may be maintained 125 the desired distance from the tubular portions of the sections of the core by means of the lugs—as, for instance, d—which serve as stops

extending between the open ends of the rings to retain the same in the desired positions, as shown, for instance, in Fig 3. The lugs may be provided with notches, as shown in Fig. 5 11, to receive the reinforcing-ring and retain the same the desired distance from the tubular portion of the sections of the core.

Referring more in detail to Figs. 12 and 13, 10 h indicates reinforcing-rings, which are partially embedded in the opposite surfaces of the radial plate or flange E. These rings are provided with shoulders H to center the friction-rings and preferably terminate distances from the cylindrical portions e^3 and e^4 of the 15 central section D of the core sufficient to form grooves, as clearly shown in Fig. 13. h^3 and h^5 indicate reinforcing-rings partially embedded in the opposite surfaces of the radial flange or plate E, the ring h^3 , with a shoulder H^3 , to 20 center the compressible ring adapted to coöperate therewith.

It is obvious that when the friction-rings are placed under tension by reason of compression or expansion the greatest strain occurs at a point diametrically opposite the 25 openings between the ends of the rings. In order, therefore, that each ring may be capable of sustaining the strain imposed upon it, it is formed of greater radial thickness or 30 width at a point diametrically opposite the opening between its ends and tapers or diminishes in radial width gradually from such point of maximum thickness toward its ends. Fig. 3 shows a compressible ring C', 35 rounded by an expandible ring B', the radial width of each of which is graduated in the manner above described.

The friction-rings are slightly spirally disposed or cambered, as indicated in Figs. 6 and 40 7, to form the function fully set forth in my copending application and patents previously referred to.

From the foregoing description it will be observed that I have invented an apparatus of 45 the type covered by my prior patents and pending application, in which the friction spring-rings are of graduated resiliency, thereby graduating the tensile strength in proportion to the weight thereof. It will also be 50 observed that in the improved apparatus forming the subject-matter of this application the frictional plates engaged by the expandible and compressible rings are provided with means rendering them capable of withstand- 55 ing the wear incident to the operation of the apparatus without becoming unevenly worn, thereby insuring uniform frictional engagement between the surfaces of the rings and the surfaces of the plates throughout the life 60 of the apparatus.

While I have described more or less precisely the details of construction, I do not wish to be understood as limiting myself thereto, as I contemplate changes in form, the

proportion of parts, and the substitution of 65 equivalents as circumstances may suggest or render expedient without departing from the spirit of my invention. I do not, however, claim the invention herein disclosed generically, inasmuch as the generic invention common to this application and to my prior application, Serial No. 116,187, filed July 18, 70 1902, is claimed in said prior application; nor do I claim the generic invention disclosed in common by this application and my prior patent, No. 715,069, dated December 2, 1902, as such common invention is claimed in said prior patent; but I do claim in this application only the features of construction not disclosed in either my said prior application or my said prior patent. 75 80

Having now fully described my invention, what I claim as new, and desire to secure by Letters Patent, is—

1. A device of the character described comprising a series of resilient elements having inclined frictional surfaces, the surfaces on adjacent elements adapted when said series of elements are subjected to compression to be relatively moved through engagement with each other thereby placing said resilient elements under tension, each of said resilient elements being of graduated resiliency. 85

2. A device of the character described comprising a series of resilient rings having inclined frictional surfaces adapted when said series of rings are compressed to be relatively moved thereby placing said rings under tension, each of said rings being of graduated resiliency. 95

3. A device of the character described comprising an expandible resilient ring of graduated resiliency and a compressible resilient ring said rings having complementally-inclined engaging frictional surfaces. 100

4. A device of the character described comprising an expandible resilient ring and a compressible resilient ring of graduated resiliency, said rings having complementally-inclined engaging frictional surfaces. 105

5. A device of the character described comprising a series of open spring-rings having inclined frictional surfaces, each of said rings being of graduated resiliency, and inclined frictional surfaces engaged by the inclined surfaces of said rings, whereby when said rings are subjected to compression they are placed under tension through the engagement of the inclined surfaces thereof with the co-operating inclined surfaces. 115

6. A device of the character described comprising a series of spirally-disposed open spring-rings having inclined frictional surfaces, each of said rings being of graduated resiliency, and inclined frictional surfaces engaged by the inclined surfaces of said rings, whereby when said rings are subjected to compression they are placed under tension 120 125

through the engagement of the inclined surfaces thereof with the coöperating inclined surfaces.

7. In an apparatus of the character described, an open spring-ring of graduated resiliency having an inclined frictional surface adapted to be engaged by a similarly-inclined surface to impart tension to the ring.

8. In a device of the character described, a spirally disposed open spring-ring of graduated resiliency having inclined frictional surfaces adapted to be engaged by similarly-inclined surfaces.

9. In a device of the character described, the combination with followers, of a core supported by said followers, a series of resilient elements having inclined frictional surfaces interposed between said followers and surrounding said core, each of said resilient elements being of graduated resiliency.

10. In a device of the character described, the combination with an expansible resilient ring, of a compressible resilient ring, said rings being of graduated resiliency and having inclined frictional engaging surfaces, and a core surrounded by and supporting said ring.

11. A device of the character described comprising a series of relatively movable elements having engaging frictional surfaces, and means for insuring a permanent uniform engagement between the frictional surfaces on said relatively movable elements.

12. In a device of the character described, the combination with a series of resilient elements, of a series of non-resilient elements supported adjacent to said resilient elements, said resilient and non-resilient elements having engaging frictional surfaces whereby when said resilient elements are flexed the frictional surfaces thereon are moved relatively to the engaged frictional surfaces on said non-resilient elements, and means for insuring a permanent uniform engagement between the frictional surfaces on said resilient and non-resilient elements.

13. In a device of the character described, the combination with a series of spring-rings, of a series of plates supported adjacent to said rings, said rings and plates having engaging frictional surfaces whereby when said rings are flexed the frictional surfaces thereon are moved relatively to the engaging frictional surfaces on said plates, and means for insuring a permanent uniform engagement between the frictional surfaces on said rings and said plates.

14. In a device of the character described, the combination with a series of spring-rings, of a series of plates, a core surrounded by and supporting said rings and plates, said rings and plates having engaging frictional surfaces whereby when the rings are flexed the said frictional surfaces thereon are moved relatively to the engaged frictional surfaces on said

plates, and means for insuring a permanent uniform engagement between the frictional surfaces on said rings and said plates.

15. In a device of the character described, the combination with a series of expansible spring-rings having inclined frictional surfaces, of a series of compressible spring-rings having inclined frictional surfaces engaging the inclined frictional surfaces on the expansible rings, a core surrounded by and supporting said rings, radially-projecting plates carried by said core, said compressible and expansible rings having frictional surfaces adapted to engage and move relatively to said plates when the rings are respectively compressed and expanded, and means for insuring a permanent uniform engagement between the frictional surfaces on said rings and said plates.

16. In a device of the character described, the combination with a series of compressible spring-rings, of a core surrounded by and supporting said rings, and radially-projecting plates carried by said core, said spring-rings having frictional surfaces adapted to engage and move relatively to said plates when the rings are compressed, said plates having grooves formed therein adjacent to the core.

17. In a device of the character described, the combination with a series of resilient elements, of a series of coöperating elements supported adjacent to said resilient elements, said resilient and coöperating elements having engaging frictional surfaces whereby when said resilient elements are flexed the frictional surfaces thereon are moved relatively to the engaged frictional surfaces on said coöperating elements, and means for insuring a permanent uniform engagement between the frictional surfaces on said resilient and coöperating elements.

18. In a device of the character described, the combination with a series of resilient elements, of a series of coöperating elements supported adjacent to said resilient elements, said resilient and coöperating elements having engaging frictional surfaces whereby when said resilient elements are flexed the frictional surfaces thereon are moved relatively to the engaged frictional surfaces on said coöperating elements, the area of the frictional surfaces on said coöperating elements corresponding in extent to the position of the frictional surfaces on the resilient elements when the latter are in their unflexed condition.

19. In a device of the character described, the combination with a series of spring-rings, of a series of plates, a core surrounded by said rings and supporting said plates, said rings and plates having engaging frictional surfaces whereby when the rings are flexed the said frictional surfaces thereon are moved relatively to the engaged frictional surfaces on said plates, the area of the frictional surfaces on said plates corresponding in extent to the

position of the frictional surfaces on the rings when the latter are in their unflexed condition.

20. In a device of the character described, the combination with a series of expandible 5 spring-rings, of a series of plates supported adjacent to said rings, said rings and plates having engaging frictional surfaces whereby when the said rings are expanded the frictional surfaces thereon are moved relatively to the 10 engaged frictional surfaces on said plates, the

frictional surfaces on said plates being cut away beyond the frictional surfaces of the rings when the latter are in their contracted condition.

In testimony whereof I sign this specification in the presence of two witnesses.

PHILLIP HIEN.
